VEHICLE DOOR LATCH

Holden W. Rightmyer, Toledo, Ohio, assignor to
 The American Swiss Company, Toledo, Ohio,
 a corporation of Ohio

Application February 15, 1941, Serial No. 379,064

3 Claims. (Cl. 292—169)

This invention relates to vehicle door locks particularly of the type having spaced inside and outside operated bolt retracting means, and an object is to produce a door latch having the new and improved features of construction, arrangement and operation hereinafter described.

For purposes of illustration but not of limitation, an embodiment of the invention is shown on the accompanying drawings in which:

Figure 1 is a side elevation of a vehicle door latch with the inside operated remote control unit removed;

Figure 2 is a side elevation of the inside operated remote control unit;

Figure 3 is a sectional view somewhat diagrammatic showing the keeper carried by the door frame and showing the latch bolt in latched position;

Figure 4 is a fragmentary elevation of a portion of the mechanism with the cover plates removed showing particularly the dogging slide and roll back and associated parts and showing the dog slide in dogging position; and

Figure 5 is a view similar to Figure 4 showing the dogging slide moved away from dogging position.

The illustrated embodiment of the invention comprises a vehicle door latch having a case plate 10 provided with the usual flange or selvage plate 11 at one edge. In the flange plate 11 is an opening through which the bolt nose 12 projects. The bolt nose 12 is connected by rivets 13 to a bolt plate 14. A spiral spring 15 has one end connected to ears 16 on the case plate 10 and has its opposite free end engaging the rear face of the bolt nose 12 to urge the latter to latching position. The bolt plate 14 extends through a guide 17 which is connected to the case plate 10 and has its rear end projecting rearwardly of the case plate and pivoted thereto as by a rivet 18 is a link 19 which is pivoted by a rivet 20 to the upper end of an upstanding arm 21 of the remote control unit. The arm 21 is pivoted to a mounting plate 22 and is retained in position by a cover plate 23 which is suitably secured to the mounting plate 22. The hub of the arm 21 is adapted to receive the usual remote control handle (not shown) for rocking the arm 21 thereby to retract the bolt nose 12 for releasing it from its keeper. A spring 24 has one end bearing against the lower portion of the arm 21 and is adapted to engage in a notch 25 for retaining the arm in its normal position with the bolt nose 12 projected.

The arm 21 has an extension 26 which abuts against the cover plate 23, thereby limiting the

clockwise or non-bolt retracting movement of the arm 21.

As diagrammatically illustrated in Figure 3, the keeper K has a rockable member 27 which is normally urged outwardly by a spring 28. An end portion 29 on the part 27 extends through an opening in the bracket plate 30. It will be apparent that the bolt nose 12 does not retract when the door is slammed shut but moves into engagement with the part 27 and rocks it about its pivot to the dotted line position indicated in Figure 3 until the bolt nose has moved into engagement with the face of the end portion 29. However, in order to open the door, the bolt nose 12 is retracted in order to clear the end portion 29, as will be readily apparent.

In order to retract the latch bolt from the outside of the door, a roll back 31 is pivotally mounted on the case plate 10 and cover plate 32, the roll back being provided with the usual hub portions which engage in openings in the case plate and cover plate respectively. As best shown on Figures 4 and 5, the roll back 31 has an arm 33 which engages a shoulder portion 34 on the bolt plate 14 so that by rocking the roll back 31 in a clockwise direction, the bolt plate is retracted against the force of the spiral spring 15. It will be understood that the roll back receives the usual handle shaft 35 which extends outside of the door and is provided with the usual operating handle (not shown). The roll back 31 is also provided with a downwardly extending arm 36.

In order to dog the roll back 31 a vertically movable slide 37 is adapted to be moved so that its free end portion is disposed between the downwardly extending arm 36 of the roll back 31 and the flange plate 11, thereby preventing clockwise retracting movement of the roll back 31. The slide 37 is carried by a downwardly projecting extension 38 integral with the case plate 10, a cover plate 39 fitting over the slide for holding it in position and assisting in guiding the movement thereof. The slide 37 has a lateral extension 40 and a toggle spring 41 is interposed between the extension 40 and the case plate 10, one end of the spring being connected to the extension 40 and the opposite end to the case plate 10. This spring serves to retain the slide either in its dogging position with respect to the roll back arm 36 or in its lower or roll back releasing position as will be readily understood.

The dogging slide 37 may be operated from the inside of the door by a rod 42 which has a knob 43 at its upper end which is disposed in any convenient position on the inside of the door

so as to be conveniently manipulated by a person within the vehicle. As shown, the rod 42 has a vertically disposed free end and the lower portion inclines downwardly and forwardly on the inside of the case plate 10. The lower end of the rod 42 passes through a vertically elongated opening 44 formed in the case plate extension 38 and is suitably secured to the dogging slide 37. It will thus be apparent that by lifting on the operating knob or button 43, the dogging slide 37 may be moved upwardly into dogging position as shown by full lines on Figure 4. It will also be apparent that by pushing downwardly on the knob or button 43, the dogging slide 37 is moved downwardly to the limit afforded by the slot 44 which is sufficient to move the upper end of the dogging slide 37 a sufficient distance away from the roll back 31 so that it may be rotated to retract the latch bolt as above explained.

The lower end of the dogging slide 37 is generally in the shape of a reversed C thereby forming a recess or cutout portion 45. Disposed within the recess 45 is a rotatably mounted cam 46 which has an actuating stem or shaft 47 which may be actuated from the outside of the door as by means of a key lock device so that by inserting the key, the shaft 47 may be turned in one direction or the other to positively move the dogging slide 37 to and from dogging position. The cam 46 is of sufficient size so that when it is turned in a counterclockwise direction, as indicated by dotted lines on Figure 5, the dogging slide 37 is moved to roll back dogging position but when the cam 46 is rocked through an arc of 180 degrees from that position or to the full line position shown in Figure 5, the dogging slide 37 is moved downwardly to roll back releasing position. When the cam is disposed in horizontal position or as indicated on Figure 4, is in its neutral position, the inside operated stem or rod 42 may be actuated for moving the dogging slide to and from dogging position. It will be manifest that by observing the position of the inside operated button or knob 43, a person can determine whether the latch is dogged or released, thereby affording convenient visible indication of the condition of the latch mechanism.

From the above description, it will be manifest that the roll back may be readily and conveniently dogged by a single dogging slide either from the inside of the door or from the outside of the door. The structure is exceedingly simple and lends itself admirably to volume production.

It is to be understood that numerous changes in details of construction, arrangement and operation may be effected without departing from the spirit of the invention especially as defined in the appended claims.

What I claim is:

1. A vehicle door latch comprising a case plate, a tensioned latch bolt movably connected to the plate, inside operated means to retract the bolt,

outside operated means to retract the bolt including a rotatable roll back, a vertically disposed dogging slide below the roll back movably connected to the case plate for movement toward

5 and away from the roll back for blocking rotation thereof in one position of the slide, said slide having a cutout which extends through one of the sides thereof and which is formed to provide spaced walls disposed at substantially right angles to the direction of movement of the slide, a rotatable cam having a nose and sides disposed in its entirety within the cut out, means to actuate the cam to engage said walls of the cut out to move the slide into and out of dogging position, said cam in one position being movable to a neutral position with its nose extending toward the rear of the cutout and its sides disposed between the opposed walls of the cutout, a lateral extension below the roll back, secured at one end

10 to the opposite side of the slide, a toggle spring connected to the opposite end of the extension and to the case plate, and means accessible from the inside of the vehicle for actuating the slide into and out of dogging position independently of the cam when the cam is in said neutral position thereof to move the slide into and out of dogging position.

2. A vehicle door latch comprising a case plate, having a vertically disposed flange at its front,

30 a tensioned latch bolt movably connected to the plate, inside operated means to retract the bolt, outside operated means to retract the bolt including a rotatable roll back, a vertically disposed spring tensioned dogging slide disposed below the

35 roll back and movably connected to the case plate at a point rearwardly of and adjacent to said front flange of the case plate for movement toward and away from the roll back for blocking rotation thereof in one position of the slide, said

40 slide having a cutout faced toward the flange of the case plate and formed with a pair of spaced opposed walls, a rotatable cam disposed substantially in its entirety in the cutout, means to actuate the cam to cause same to engage said walls of

45 the cutout and thereby move the slide into and out of dogging position, said cam in one position being movable to a neutral position substantially at right angles to the face plate and between the opposed walls of the cutout, and means accessible

50 from the inside of the vehicle for actuating the slide when the cam is in said neutral position within the cutout thereof to move the slide into and out of dogging position.

3. A vehicle door latch in accordance with

55 claim 2, wherein the means to actuate the slide when the cam is in neutral position includes an inclined rod having an end disposed rearwardly of the roll back and in front of the toggle spring and extending through and slidably in an elongated opening provided therefor in the case plate

60 and connected to the slide.

HOLDEN W. RIGHTMYER.
